[57] CLAIM

The ornamental design for a lighted sight pin for archery scopes, as shown and described.

DESCRIPTION

FIG. 1 is a perspective view of a lighted sight pin for archery scopes, showing my new design;

FIG. 2 is an enlarged front elevational view thereof;

FIG. 3 is an enlarged back elevational view thereof;

FIG. 4 is an enlarged side elevational view thereof;

FIG. 5 is an enlarged elevational view taken from the side opposite that shown in FIG. 4;

FIG. 6 is a top plan view thereof; and

FIG. 7 is a bottom plan view thereof.

The broken lines representation of a scope is for illustrative purposes only.

FIG. 1
